INVENTOR.

S. F. Hammer

UNITED STATES PATENT OFFICE.

STUART F. HAMMER, OF MACOMB, ILLINOIS.

MACHINE FOR SHOCKING GRAIN.

SPECIFICATION forming part of Letters Patent No. 242,198, dated May 31, 1881.

Application filed March 10, 1881. (No model.)

To all whom it may concern:

Be it known that I, STUART F. HAMMER, of Macomb, in the county of McDonough and State of Illinois, have invented a new and 5 useful Machine for Shocking Grain, of which the following is a specification.

In the drawings, Figure 1 is a perspective view of my invention. Fig. 2 is a detached portion of the mechanism not clearly shown in 10 Fig. 1.

The nature and object of this invention is to construct a suitable machine for shocking grain, which can be attached to a self-binding reaper or drawn along its side by other means; 15 and its novelty consists in an adjustable platform placed between suitable runners or wheels with a lever-frame and mechanism for raising and lowering it, as hereinafter described and claimed.

20 In the drawings, Fig. 1, A A represent the runners, between which an adjustable frame, D, is placed, which is constructed of suitable bars, as shown, with a space between them equal to their thickness, and they are secured 25 firmly together by suitable bolts, which pass through the bars and through the thimbles s s s, which keep the bars the right distance apart. The frame D is attached to the inside of the runners by means of the elbow-cranks 30 a a a. (See Fig. 2.) The pins i i in said cranks pass through the runners, and the pins n n pass through a bar at each side of the frame. The rods o o are attached to the elbow-cranks, as shown, to give concert of action. 35 The lever-frame J is pivoted to the inside of the runners at c c. The projecting arms t t are slotted at their outer ends to receive the pins n n.

The operation is as follows: The machine, 40 as shown in Fig. 1, is attached to a self-binding reaper, or horses hitched to the tongue C

and drawn along the side of the reaper, so that the sheaves, as they come from the reaper, will fall on the inclined side B. The operator takes his place on the platform D, turns the 45 fender b to its shown position, and as the sheaves come from the reaper he sets them up against the fender b on the rear end of the platform, and when a sufficient number of the sheaves have been set together to form a shock 50 the operator then turns the fender b around out of the way, then reaches forward and takes hold of the lever-frame J, which has been held firm by suitable mechanism, (not shown,) and draws the lever-frame rearward until the plat- 55 form D strikes the ground, which is done in an instant, and in so doing the stubbles pass up between the opening in the platform and catch into the butts of the sheaves in the shock and hold it while the platform is drawn out 60 from under it, leaving the shock setting up on the ground in good condition. The lever-frame is then thrown forward, raising up the plat- 65 form to its shown position, and the fender is again turned to its shown position and another shock commenced, as before.

Having thus fully described my invention, what I claim as new, and desire to secure by Letters Patent, is—

1. The adjustable platform D, lever-frame 70 J, elbow-cranks a a a, and rods o o, all operating jointly together substantially as shown and described, for the purpose set forth.

2. In combination with the adjustable platform D, lever-frame J, elbow-cranks a a a, 75 and the inclined side B, substantially as and for the purpose specified.

S. F. HAMMER.
